UNITED STATES PATENT OFFICE.

WILBUR G. LAIRD, OF NEW YORK, N. Y., ASSIGNOR TO THE IMPROVED EQUIPMENT COMPANY,
OF NEW YORK, N. Y., A CORPORATION OF COLORADO.

GAS-RETORT COLLAR.

No. 888,622.

Specification of Letters Patent.

Patented May 26, 1908.

Application filed May 27, 1907. Serial No. 375,783.

To all whom it may concern:

Be it known that I, WILBUR G. LAIRD, a citizen of the United States, residing at New York, in the county of New York and State 5 of New York, have invented certain new and useful Improvements in Gas-Retort Collars, of which the following is a specification, reference being had to the drawings accompanying and forming part of the same.

10 My invention relates to gas-making retorts, more particularly to the means for closing the opening or mouth of the retort through which the material to be heated is introduced and through which the resulting 15 gas is led off. The plan now commonly employed for providing a closure for the retort mouth is to fit on the neck thereof a mouthpiece, say of cast iron, to which the closure is hinged. This mouthpiece is usually secured 20 to the retort by means of bolts extending into the wall of the mouth from the edge thereof, in apertures provided for the purpose in the process of molding or forming the retort. As will be readily understood, this 25 method puts considerable tensional strain on the clay of the retort, and breakages are therefore frequent. In any case there is liability of breakage, with its attendant loss and inconveniences.

30 The primary object of my invention is to provide means for securing the mouthpiece to the retort which shall subject the retort to minimum tensional strains, and for securing depend rather on compression 35 strains, to which, as is well known, structures of clay or similar material have considerable resistance. As a result the liability of breakage is very materially lessened and the retorts generally have much longer life.

40 Retorts of the kind referred to are usually assembled one above the other in what is known as a "gas bench", while the gas is led away by means of stand-pipes extending vertically from the mouthpieces. Where the 45 bench contains a considerable number of retorts, say more than three in a vertical row, there is usually insufficient room to provide a stand-pipe for each retort and it is therefore customary to connect two or more retorts 50 together, and conduct the gas away by means of a stand-pipe from the uppermost. In such case the breakdown of one of the retorts puts out of use those connected with it; but on the other hand the connecting pipes unite 55 the retort mouthpieces, making one aid in

supporting the other, thus having the effect of strengthening the whole and making breakage of the retorts less likely to occur. It is clear of course that where each retort has its own stand-pipe none is affected by the 60 breakage of another, but at the same time the advantage of mutual support is not available.

It is therefore a further object of my invention to provide for the retort a collar to which the mouthpiece can be secured and which can 65 be connected or locked with its upper and lower neighbors in the bench so as to obtain mutual support, and also to provide a connection of such character that strains produced by one mouthpiece aiding in supporting 70 another will neutralize, to a degree at least, other strains which tend to break the supporting mouth.

The foregoing advantages, and others, are secured by certain novel features of construction, arrangements of parts, and combinations of elements, constituting my invention. The same will be more readily understood from a more or less detailed description of the preferred embodiment thereof, 75 and for that purpose reference may be had to the annexed drawings, in which such embodiment is illustrated.

In the drawings, Figure 1 shows in front elevation a portion of a gas bench, showing 85 three retorts and stand-pipes therefor. Fig. 2 is a sectional view of a portion of the front of a gas bench, showing retorts provided with my improved collar and interlocking devices. Fig. 3 is a front view of the retort collar, and 90 Fig. 4 is a top plan view thereof, with a portion of the upper part broken away. Fig. 5 is a detail view of the key used to lock two collars together.

As stated, Fig. 1 shows three retorts, arranged in a gas bench. The mouthpieces of the retorts are indicated by 1, 2, 3 and the stand-pipes extending therefrom are indicated by 4, 5, 6 respectively. The mouths may be of the form shown, that is, with flat 100 bottoms and arched tops, and in the particular embodiment of my invention herein illustrated and described my improved collar is shown as of a form to fit such mouths.

My novel retort collar assembled on the 105 retort, with a mouthpiece secured to the collar, is shown in Fig. 2. The collar 7 is secured around the retort mouth, preferably in the manner hereinafter described, and the mouth piece 8 is secured to the collar, preferably 110

detachably, as by means of bolts shown at 9. The mouthpiece is provided with a suitable closure, not shown, secured thereto in any convenient and suitable way. From the 5 mouthpieces the gas is conducted off by standpipes, as 4, 5, 6 in Fig. 2.

The collar is shown in Figs. 3 and 4, where it is seen to consist of two parts, the lower, 10, conforming to the bottom of the retort mouth, and the upper, 11, conforming to the top of the mouth. At the adjacent edges of the parts are registering grooves 12, formed preferably by vertically extending ribs 13. These parts are fitted around the mouth of 15 the retort as shown in Fig. 2, and are bound firmly thereon by bolts 14 in the grooves just mentioned. The strain produced by these bolts is compressional, which the material of the retort, and the arch form thereof at the 20 mouth, are well able to withstand. Interposed between the collar and the retort is a cement packing, for example a "rust" packing composed of iron filings or turnings mixed with a suitable quantity of clay and sal-ammoniac solution, to make a close fit between 25 the retort and collar, give the two a better grip on each other, and obviate any slight difference in contour, which might result in greater strain at one point than another if no 30 packing were used.

From the foregoing it will be seen that the only strain exerted by the collar is compressional, and this strain the retort is, as before explained, well able to withstand. However, the strain produced by the mouthpiece 35 and standpipe is chiefly exerted as a turning moment tending to throw the top of the mouthpiece forward, in other words, to turn the collar on its base as a pivot, thus tending 40 to break off the mouth portion of the retort. To overcome this strain the mouthpieces may be locked together in the manner now to be described.

On the bottom of the collar is a transverse 45 rib 15, and on the top, preferably at the center thereof, is a lug 16, located rearward of the rib 15. Hence when the retorts are arranged as shown in Figs. 1 and 2 the lug on each collar will lie to the rear of the adjacent 50 rib on the collar just above. Between the lug and the rib a key 17, preferably tapering as shown in Fig. 5, is then driven, so as to bear at its top edge on the rib and at its bottom edge on the lug. The result is, as will 55 be readily seen, that the strain which tends to throw the top of the lower collar outward is exerted against the key and through the latter against the bottom of the upper collar; at the same time the strain of the mouth 60 piece and standpipe on the upper collar tends to throw the bottom of the collar inward rather than outward, thus exerting itself against the opposite strain exerted by the top of the lower collar. Hence the 65 strains which otherwise would tend to dis-

tort and in consequence break the retorts are not merely neutralized but are even utilized to hold the collars more firmly in position. With the mouthpieces thus braced or supported the retorts are also better able to 70 withstand the careless use of the rake employed for handling the material in the retort. This rake is long and heavy, and in the hands of a careless workman often strikes the mouthpiece with considerable 75 force, sometimes sufficient to break the retort.

In order to permit the retorts, when necessary or desirable, to be arranged as in Fig. 1, with one or more off-set to the right or left 80 of the vertical series to conform to the arched top of the retort oven, shown in dotted lines at 18, and still permit the mouthpieces to be locked together as just described, the ribs 15 are made of some length, for example extending 85 substantially the full width of the bottom. Thus in Fig. 1, retort 1 lies considerably to the right of retort 2, but the rib on the former nevertheless extends past the lug on the latter and the two can therefore be 90 keyed together as shown.

As previously stated, the devices herein specifically shown and described constitute merely the preferred embodiment of my invention, which is capable of wide variation 95 in form, arrangement, number, and proportions of parts, etc., without departing from the proper scope of the invention as defined by the following claims.

What I claim is:

1. The combination with a retort, of a collar secured around the mouth thereof and constructed to exert compression on the portion of the retort engaged by the collar, and a mouthpiece secured to the collar, as 100 set forth.
2. The combination with a retort, of a collar secured around the mouth thereof and constructed to exert compression on the portion of the retort engaged by the collar, 110 and a mouthpiece detachably secured to the collar, as set forth.
3. The combination with a retort, of a collar composed of radially separable parts, means for drawing the said parts firmly together around the mouth of the retort, and a mouthpiece secured to the collar. 115
4. A retort collar composed of radially separable parts, and means for drawing the said parts together on the retort around the 120 mouth thereof, as set forth.
5. A retort collar composed of radially separable parts, and binding bolts arranged to draw the said parts together on the retort around the mouth thereof, as set forth. 125
6. A retort collar composed of radially separable parts formed at their adjacent edges with recesses to receive binding devices for binding the parts around the mouth of a retort, as set forth. 130

7. A retort collar composed of radially separable parts having at their adjacent edges ribs forming registering grooves for the reception of binding bolts, as set forth. 30
- 5 8. The combination with a retort, of a collar composed of radially separable parts, means for binding the said parts firmly on the retort around the mouth thereof, and a packing between the collar and the retort, 35
- 10 whereby the pressure of the collar will be substantially uniform on the retort around the mouth, as set forth.
9. The combination with a plurality of retorts arranged one above the other, of collars on the retorts around the mouths thereof, and means for locking the top of a collar to the bottom of the collar next above, as set forth. 40
- 15 10. In a gas bench, the combination with retorts arranged one above the other with their mouths at the front of the bench, of collars on the retorts around the mouths thereof, and means for causing strains tending to throw the top of the collar outward to 45
- 20 be exerted against the bottom of the collar next above, as set forth.
- 25 11. In a gas bench having retorts arranged one above the other, the combination with a retort and the one next above, of collars on the retorts around the mouths thereof, the upper collar having on its bottom a transverse rib and the lower collar having on its top a lug located to the rear of the said rib, and a key between the rib and the lug, as set forth. 50
- 30 12. A retort collar having on its bottom a rib, and on its top a lug rearward of the rib, as set forth. 55
- 35 13. A retort collar having a flat bottom, and a transverse rib on the bottom, extending on either side of the center thereof, as set forth. 60
- 40 14. A retort collar having a flat bottom, and a transverse rib on its bottom, extending from side to side thereof. 65
- 45 15. A retort collar having a flat bottom and an arched top, a rib on the bottom thereof, and on the top a lug rearward of the rib, as set forth. 70
- 50 16. A retort collar composed of radially separable parts, a rib on the bottom of the collar, and on the top of the collar a lug rearward of the rib, as set forth. 75
